UNITED STATES PATENT OFFICE.

EDWARD J. BARRETT, OF NEW YORK, N. Y.

LOCK DEVICE FOR SHADE ROLLERS.

Application filed February 3, 1923, Serial No. 616,692. Renewed January 3, 1925.

To all whom it may concern:

Be it known that T. EDWARD J. BARRETT, a citizen of the United States, and residing at New York city, in the county of New York and State of New York, have invented certain new and useful Improvements in Lock Devices for Shade Rollers, of which the following is a specification, such as will enable those skilled in the art to which it appertains to make and use the same.

This invention relates to means for supporting shade rollers and the like in a window frame and for locking the same against accidental displacement therein, and the object of the invention is to provide a device of this class provided with means whereby a shade roller or the shank thereof, may be readily attached to and detached from its support; a further object being to provide a compact device of the class specified whereby a decided saving of the material employed is effected in the production of the device; a further object being to provide an improved spring construction for retaining and locking the shank of a shade roller within the device; a still further object being to provide a device of the class specified which may be mounted in different positions in a window frame as well as the provision of a device of this class wherein the separate parts are permanently attached to form a unitary device; and with these and other objects in view the invention consists in a device of the class and for the purpose specified which is simple in construction, efficient in use and which is constructed as hereinafter described and claimed.

The invention described and claimed herein is an improvement on that described and claimed in prior applications filed Nov. 23, 1920, Ser. No. 425,972 and Jan. 9, 1922, Ser. No. 527,977; and the invention is fully disclosed in the following specification, of which the accompanying drawing forms a part, in which the separate parts of my improvement are designated by suitable reference characters in each of the views, and in which:

Fig. 1 is a side view of the top portion of a window frame and indicating one use of my improved lock device;

Fig. 2 a detail view of one of my improved shade roller supporting devices shown in Fig. 1;

Fig. 3 a partial section on the line 3—3

of Fig. 2 and indicating a part of a shade roller;

Fig. 4 a view similar to Fig. 2 but showing a modified form of device and a different method of mounting the same in a window frame;

Fig. 5 a partial section on the line 5—5 of Fig. 4;

Fig. 6 a perspective detail view of the spring shown in Figs. 4 and 5; and,

Fig. 7 a view similar to Figs. 2 and 3 but showing a modification and illustrating another method of mounting the device in the window frame.

In Fig. 1 of the drawing I have indicated at 10 the top portion of a window frame and at 11 the side portions of said frame between which the shade roller 12 is mounted. The shank 13 at one end of the shade roller is mounted in a suitable keeper 14, while the shank 15 or angular shank is mounted in one of my improved support and lock devices 16.

My improved lock device 16 in the construction shown in Figs. 1 to 3 inclusive is composed of two parts 17 and 18, the part 17 being substantially box-shaped in form, comprising a top plate 19 having an elongated aperture 20 opening outwardly through one side of the part 17 as shown at 21, and at the opposite sides of the top 19 are downwardly extending side walls 22 having projecting apertured ears 23 by means of which the part 17 may be secured to the window frame or one side 11 thereof as shown.

The other part 18 of my improved device is preferably composed of spring material, and one end thereof is riveted or otherwise secured to the part 17 as shown at 24 and adjacent to the attached end, the part 18 is looped as shown at 25 to give the required spring properties to said part; and the free end portion of said part extends beyond one side of the part 17 and is preferably curved as shown at 26. The part 18 is provided with an elongated aperture 27 which registers with the aperture 20 in the top 19 of the part 17. The keeper 14 shown in Fig. 1 may be of the same general construction as the part 17 of the device shown in Figs. 1 to 3 inclusive, but instead of being provided with the elongated aperture 20 a suitable aperture will be provided to receive the shank 13.

In the construction shown in Figs. 1 to 3

inclusive, my improved device is mounted with the spring part 18 directed inwardly of the window frame or at right angles to the vertical plane of the window frame, and in the use of the device after the shank 13 has been placed in the aperture of the keeper 14, the shank 15 is passed over the curved end portion 25 of the spring part 18 and forced inwardly, in which operation 10 the spring is depressed and the shank 15 passes through the aperture 20 and into the aperture 27, and the spring part 18 then moves outwardly to lock and retain the shank 15 against displacement in the device 15 16. When it is desired to remove the shade roller the spring part 18 is depressed by hand and the shade roller is removed as will be apparent.

In Figs. 4, 5 and 6 of the drawing, I have 20 shown a slight modification in which the spring part 18 instead of being attached to the part 17, and instead of being provided with the looped portion 25, is curved at one end as shown at 28 and provided with an 25 enlarged cross head 29, the opposite ends of which are apertured and the cross head 29 is of such form as to register the apertures thereof with the apertures of the ears 23 of the part 17 so that the passage of nails, 30 screws, or the like through the apertures of the ears 23 will operate to retain the spring part 18 as well as the part 17 in predetermined position. It will also be noted that the device shown in Figs. 4 to 6 inclusive is 35 mounted in an angular position on the window frame, or one of the side members 11 thereof, or at an angle of approximately forty-five degrees to the vertical plane of the window frame instead of at right angles as 40 shown in Fig. 2 of the drawing. With the above exceptions the construction and operation of the device shown in Figs. 4 to 6 inclusive will be exactly the same as that shown in Figs. 1 to 3 inclusive.

In Fig. 7 of the drawing, I have shown 45 another modification in which I employ substantially the same spring part 18 as shown in Figs. 4 to 6 inclusive, but in Fig. 7 the part 17 or the aperture 20 thereof opens outwardly through the opposite side 50 of said part 17 as shown at 30, and with a device of this construction it is supported in a window frame or on one of the side members thereof with the spring part 18 in 55 the same vertical plane as the window frame and with the free or projecting end of the spring part directed downwardly. It will be apparent that with this form of construction 60 the shank 15 of the shade roller is passed downwardly into the device and is automatically passed into the aperture 27 of the spring part 18, and said shank is released by depressing the protruding end portion 26 of the part 18.

65 From the foregoing it will be apparent

that the distinctive features of my present invention over that shown and described in my pending applications are the provision of a comparatively short part or casing 17 and a correspondingly short spring device 70 effecting a decided saving in the amount of material employed in the production of my improved device and also permitting of the mounting of the device on small flat surfaces on the side members of a window frame, and while I have shown certain details of construction for carrying my invention into effect, it will be understood that I am not necessarily limited to these details, 75 and various changes therein and modifications thereof may be made, within the scope of the appended claims without departing from the spirit of my invention or sacrificing its advantages.

Having fully described my invention, 80 what I claim as new and desire to secure by Letters Patent, is:—

1. A lock device for the shank of shade rollers comprising a casing, the front wall of which is apertured, and a part composed of resilient material mounted within the casing and apertured to register with the aperture of the casing.

2. A lock device for the shank of shade rollers comprising a casing, the front wall of which is apertured, a part composed of resilient material mounted within the casing and apertured to register with the aperture of the casing, and the aperture of the casing opening outwardly through one side thereof to permit of the passage of the shank of a shade roller into said aperture.

3. A lock device for the shank of shade rollers comprising a casing, the front wall of which is apertured, a part composed of resilient material mounted within the casing, the aperture of the casing opening outwardly through one side thereof to permit of the passage of the shank of a shade roller into said aperture, and one end of said part being fixed, and the free end portion of said part being slightly curved where the aperture opens outwardly through the casing to permit of the passage of the shank of a shade roller thereover.

4. A lock device for the shank of shade rollers, said device comprising a casing having an elongated aperture opening outwardly through one side thereof, means whereby said casing may be attached to a suitable support, and a spring member within said casing and having an aperture therethrough registering with the aperture of said casing.

5. A lock device for the shank of shade rollers, said device comprising a casing having an elongated aperture opening outwardly through one side thereof, means whereby said casing may be attached to a suitable support, and a spring member within said casing and having an aperture therethrough

registering with the aperture of said casing, one end portion of said spring member being attached and fashioned to give the required spring properties thereto.

5 6. A lock device for the shank of shade rollers, said device comprising a casing having an elongated aperture opening outwardly through one side thereof, means whereby said casing may be attached to a suitable 10 support, a spring member within said casing and provided with an aperture adapted to register with the aperture of said casing, one end portion of said spring member being attached and fashioned to give the required 15 spring properties thereto, and said spring member being curved in juxtaposition to the aperture of said casing to permit of the insertion of the shank of a shade roller.

20 7. A lock device for the shank of shade rollers, said device comprising a casing having an elongated aperture opening outwardly through one side thereof, means whereby said casing may be attached to a suitable 25 support, a spring member within said casing and provided with an aperture adapted to register with the aperture of said casing, one end portion of said spring member being attached and fashioned to give the required 30 spring properties thereto, said spring member being curved in juxtaposition to the aperture of said casing to permit of the insertion of the shank of a shade roller, and one end of said spring member projecting 35 through the casing.

8. A support and lock device for the shank of shade rollers comprising a comparatively small box-shaped casing adapted to be secured to a suitable support, and the front wall of which is provided with an aperture opening outwardly through one end thereof, a spring member mounted and secured within said casing, said spring member being apertured to receive the shank of 40 a shade roller and to register with the aperture of said casing, and one end portion of the spring member being free and protruding through the casing.

45 9. A support and lock device for the shank of shade rollers comprising a comparatively small box-shaped casing adapted to be secured to a suitable support, and the front wall of which is provided with an aperture opening outwardly through one end thereof, a spring member mounted and secured within said casing, said spring member being apertured to receive the shank of a shade roller and to register with the aperture of 50 said casing, one end portion of the spring member being free and protruding through the casing, and the protruding portion of said spring member being curved.

60 10. A support for the shanks of shade

rollers comprising a substantially box-shaped casing composed of top and side 65 walls, said side walls having projecting ear members to facilitate the mounting of the casing on a suitable support and the top wall of said casing being apertured, and a spring member mounted within the casing and having an aperture therethrough registering with the aperture of said casing and adapted to receive and retain the shank of a shade roller against displacement in said casing.

70 11. A support for the shanks of shade rollers comprising a substantially box-shaped casing composed of top and side walls, said side walls having projecting ear members to facilitate the mounting of the casing on a suitable support and the top wall of said casing being apertured, and a spring member mounted within the casing and having an aperture therethrough registering with the aperture of said casing and adapted to receive and retain the shank 75 of a shade roller against displacement in said casing, said spring member being fixed to and forming a unitary part of said casing.

80 12. A support for the shanks of shade rollers comprising a substantially box-shaped casing composed of top and side walls, said side walls having projecting ear members to facilitate the mounting of the casing on a suitable support and the top wall of said casing being apertured, and a spring member mounted within the casing and having an aperture therethrough registering with the aperture of said casing and adapted to receive and retain the shank 85 of a shade roller against displacement in said casing, said spring member being fixed to and forming a unitary part of said casing, and the free end portion of said spring member projecting through the casing.

90 13. A support for the shanks of shade rollers comprising a substantially box-shaped casing composed of top and side walls, said side walls having projecting ear members to facilitate the mounting of the casing on a suitable support and the top wall 95 of said casing being apertured, and a spring member mounted within the casing and having an aperture therethrough registering with the aperture of said casing and adapted to receive and retain the shank of a shade 100 roller against displacement in said casing, said spring member being fixed to and forming a unitary part of said casing, and the free end portion of said spring member projecting through the casing, and the protruding portion being curved.

105 In testimony that I claim the foregoing as my invention I have signed my name this 30th day of January, 1923.

EDWARD J. BARRETT.
